UNITED STATES PATENT OFFICE.

AUGUST BOUCHERY, OF NEW YORK, N. Y., ASSIGNOR, BY MESNE ASSIGNMENTS, TO WATERBURY-WALLACE COMPANY, INC., OF NEW YORK, N. Y., A CORPORATION OF NEW YORK.

PORTABLE ELECTRIC-LAMP STAND.

1,189,533.

Specification of Letters Patent.

Patented July 4, 1916.

Original application filed August 22, 1914, Serial No. 858,009. Divided and this application filed January 11, 1915. Serial No. 1,558.

To all whom it may concern:

Be it known that I, AUGUST BOUCHERY, a citizen of the United States, residing in the borough of Brooklyn, in the county of 5 Kings, city and State of New York, have invented new and useful Improvements in Portable Electric-Lamp Stands, of which the following is a specification.

This invention relates to portable electric 10 lamp stands, and it is the primary object of the invention to provide a lamp stand of this character having means to clamp and support the stand from a suitable support, such as a bedstead, dresser, chair, desk or other 15 object, and to provide a stand with a suction supporting device to sustain the stand from a non-porous surface at an angle to the horizontal.

The present application is a division of 20 my co-pending application filed August 22, 1914, Serial No. 858,009, Patent 1,132,532, March 16, 1915, covering a lamp of this character in which the parts may be readily and quickly disassembled and packed into a 25 small, neat and compact structure to take up a minimum amount of space, the supporting base and a shade for the lamp being constituted to be releasably connected to form a receptacle in which to inclose a lamp socket, 30 a connecting plug and a length of electric current conductors to the ends of which the lamp socket and plug are connected, the lamp base and shade when connected to form a receptacle also inclosing and 35 concealing the shade supporting means connected to the shade and the means to clamp the stand to a support and to sustain it from a non-porous surface.

The principal object of the present invention is to provide novel means, in the 40 form of a spring normally housed and concealed by the base to permit of setting the stand upon a flat surface and coöoperating with the base as a clamp, to support the stand from a suitable object, and to the slidably mounting of a lamp supporting stem in the base, the inner end of said stem being connected to the clamping spring in the base and normally maintained in its upper position 45 by said spring. A suction supporting device is connected to the lamp supporting stem within the base, the tension of the spring when the stand is supported by the suction device exerting an outward push on

the stem and drawing the stand toward the 55 sustaining surface to serve as a firm and rigid backing for the suction supporting device and preventing sagging of the stand.

In the drawings accompanying and forming a part of this specification, Figure 1 is a 60 side elevation of an incandescent lamp supporting stand, partly broken away, and illustrating an embodiment of my invention. Fig. 2 is a side elevation showing the manner of clamping and supporting the stand 65 from a suitable object. Fig. 3 is a side elevation, partly broken away, to illustrate the manner of sustaining the stand from a surface at an angle to the horizontal by means of the suction device. Fig. 4 is a bottom 70 view of the shade. Fig. 5 is a side elevation showing the manner of constructing the lamp supporting stand to permit of the tilting of the lamp to an angle relative to the axis of the lamp supporting stem; and Fig. 75 6 is a sectional side elevation showing the base and shade connected with the socket, plug, current conductor and the lamp stand and shade supporting means inclosed and concealed by the base and shade. 80

Similar characters of reference designate like parts throughout the different views of the drawings.

In the embodiment of my invention illustrated in the drawings I have shown the 85 same as consisting of a base B substantially of bell-shape with the bottom flaring out, and a shade S substantially of dome-shape having means, such as a pair of resilient or yielding loops 7, to support the shade from 90 a globe or bulb at opposite sides to have adjustment about the longitudinal axis of the lamp and also to any angle on an axis transverse to the bulb. The shade is constructed of a suitable resilient or yielding 95 material and the periphery of the bottom is of slightly greater diameter than the bottom of the base to permit it to engage over the bottom of the base, and the bottom of the shade is so constructed that portions thereof, 100 as at s, in the form of inwardly extending projections will yieldingly engage with the base. As the shade and base are being connected the material of the shade will give or spring and when connected the projections 105 will releasably hold the shade to the base. A stem 8 is slidably mounted in the top of the base, and a transverse member 11 in the

form of a disk having an opening concentric with the opening in the top of the base is fastened in the base providing a long bearing for the stem and preventing canting thereof, and to which stem a lamp socket 9 is adapted to be removably connected.

To support the lamp stand from an object, such as a bedstead, dresser, chair or the like, I provide a clamping member to 10 coöperate with the base as a clamp. This member consists of a coiled spring 10 inclosed by and connected to the base and preferably wound to conform to the base. The inner coil or whirl of the spring is connected to the stem 8 within the base and the outer coil or whirl engages in a bead at the bottom of the base, as shown at 12, Figs. 1 and 6. The spring at a point between the ends is fixed to the base as by soldering, 20 as shown at 13, Figs. 1 and 6. By this construction a whirl or whirls of the spring adjacent the lower end may be pulled out from the base to engage an object *o* and coöperate with the base as a clamp to firmly 25 secure the lamp to such support, as shown in Fig. 2. The coils of the spring adjacent the upper end and secured to the stem 8 tend to maintain the stem in its uppermost position but permit said stem to be pushed 30 into the base for a purpose to be hereinafter described.

The stem 8 at its end within the base and within the spring has a suction supporting device, such as a suction cup of rubber 14, 35 to support the lamp from a surface which is at an angle to the horizontal, as shown in Fig. 3. To cause the suction cup to engage with the supporting surface the stem 8 is pushed inward against the tension of the 40 upper coils of the spring forcibly pressing the suction cup against the surface. As the pressure is released on the stem the spring will exert an outward pressure on the stem and constantly exert a pull on the suction 45 cup. This pull on the cup facilitates the holding of the lamp by the cup as it constantly tends to create a vacuum in the cup. Furthermore, the tension of the spring 50 presses the bottom of the base firmly against the supporting surface, whereby the base serves as a backing to prevent sagging and wobbling of the lamp.

As stated the lamp socket is removably connected to the stem 8 and is adapted to 55 be connected thereto to extend co-axially with the stem or at an angle thereto. For this purpose the stem 8 is made of a pair of sections pivotally connected, as at 15, to swing on an axis transverse to the axis of the stem. The free end of the outer stem section is provided with screw threads 17. The socket has a tubular portion 19 internally screw threaded to engage over the end 60 of the stem 8 and the screw threads on the stem and tubular socket portion are so con-

stituted that by giving the socket a partial rotation it will be firmly connected to the stem.

The socket is connected to one end of current conductors 20, the other end of 70 which are connected to a plug 21 to connect the lamp to the source of current at some distance away from the place where the lamp is to be used. The conductor, socket and plug are adapted to be placed into the 75 shade and be inclosed thereby when it is connected to the base, the spring 10 lying contiguous to the inner surface of the base permitting the shade supporting loops 7 to engage within the coils of the spring, as 80 shown in Fig. 6.

From the foregoing description it will be obvious that I have produced a portable electric lamp which can be disassembled and packed into a compact structure to take up 85 a minimum amount of space, for instance as shown by the dotted lines 22 in Fig. 6, in a traveling bag or case.

Variations may be resorted to within the scope of my invention. 90

Having thus described my invention, I claim:

1. A portable lamp stand comprising a base, a lamp supporting stem slidably mounted in the base, a suction cup connected to the stem, and a spring carried by the base and connected to the stem to normally maintain the stem in position with the suction cup within the base, said spring being arranged to coöperate with the base 100 to clamp the lamp to a support at the base.

2. In a portable lamp the combination of a hollow base, a stem mounted in the base to have longitudinal movement relative to the base, a lamp connected to the outer end of 105 stem, a suction cup connected to the inner end of stem, and a spring to retract the stem, said spring being arranged so that a portion may be withdrawn from the base to coöperate with the base and clamp the lamp 110 to a support at the base.

3. A portable electric lamp stand, comprising a base, a lamp supporting stem movable longitudinally with respect to the base, a suction device carried by the stem, and a 115 spring clamping member carried by the base to coöperate with the base to clamp and support the lamp at the base, and said clamping member adapted to retract the stem.

4. In a lamp stand the combination of a 120 base, a clamping member within the base arranged to be withdrawn and coöperate with the base as a clamp, a lamp supporting stem longitudinally slidable in the base and normally maintained in its uppermost position by the clamping member, and a suction device connected to the stem, said stem and suction device movable as a unit with respect to the base against the action of the clamping member. 125

5. In a lamp stand the combination of a base, a coiled spring secured within and housed by the base, a portion of the spring being arranged to be withdrawn from the base to 5 coöperate therewith as a clamp, a lamp supporting stem slidably mounted in the base and connected to the spring, and a suction device connected to said stem within the base and arranged to be projected out from 10 the base against the tension of the spring by the stem, substantially as and for the purpose specified.

6. In a portable lamp the combination of a base, a stem longitudinally slidable and 15 rotatable in the base, a lamp carried by said stem, a suction cup connected to the stem, a spring within the base to normally maintain the stem in its uppermost position and the suction cup within the base and ar- 20 ranged to have a portion withdrawn from the base to coöperate therewith as a clamp, and said stem, suction cup and lamp mov-

able as a unit with respect to the base against the tension of the spring, substan- 25 tially as and for the purpose specified.

7. In a portable lamp the combination of a base, a stem consisting of pivotally connected sections mounted in the base to have longitudinal movement and arranged to have an electric lamp socket removably connected thereto, a suction cup connected to and movable with the stem, and a spring within the base connected to the stem to normally maintain the stem in its uppermost position and the suction cup within the base, 30 and said spring arranged to have a portion thereof withdrawn from the base to coöperate with the latter as a clamp, substantially as and for the purpose specified. 35

AUGUST BOUCHERY.
